CLAIM

The ornamental design for an emery board with replaceable end attachments, as shown and described.

DESCRIPTION

FIG. 1 is a top plan view of an emery board with replaceable end attachments, showing my new design; FIG. 2 is an elevational view of one side, the opposite side being in mirror symmetry; FIG. 3 is a bottom plan view;

FIG. 4 is an elevational view from the left-hand end; and

FIG. 5 is an elevational view from the right-hand end.
